DESIGN FOR A TILE

Roy W. Schweiker, Lansdale, Pa., assignor to Franklin Tile Company, Lansdale, Pa., a corporation of Pennsylvania

Application August 17, 1940, Serial No. 94,475

Term of patent 14 years

To all whom it may concern:

Be it known that I, Roy W. Schweiker, a citizen of the United States, residing at Lansdale, in the county of Montgomery and State of Pennsylvania, have invented a new, original, and ornamental Design for a Tile, of which the following is a specification, reference being had to the accompanying drawing, forming part thereof.

Fig. 1 is a top plan view of a tile showing my new design;

Fig. 2 is an edge view looking toward the left of Fig. 1; and

Fig. 3 is an edge view looking from the bottom of Fig. 1.

I claim:

The ornamental design for a tile, as shown.

ROY W. SCHWEIKER.
